UNITED STATES PATENT OFFICE.

CHARLES H. VON GLAHN, OF BROOKLYN, NEW YORK.

BOX-MAKING MACHINE.

Application filed November 21, 1924. Serial No. 751,245.

This invention relates to machines for making paper boxes, and involves carrying forward the invention set forth in my prior Patent No. 1,516,165, issued November 18, 5 1924, for box making machines.

A broad feature of the present invention consists in a novel organization and arrangement of mechanism to strip the boxes or trays from the die on which they are formed, 10 to transfer the boxes to a stacking mechanism, to stack the boxes in piles, and to remove the piles from the stacking station after a predetermined number of boxes have been arranged in each pile.

15 Another feature of this invention consists in box forming, stacking, and counting mechanism adapted to operate in cycles, whereby after the formation of a pile of boxes containing a predetermined number, the boxes 20 will be automatically removed and a new pile started.

The illustrated machine comprises a stripping mechanism adapted to remove finished boxes from the die, and a gripping mechanism 25 arranged adjacent to the die to receive the boxes as they are removed. The gripping mechanism is movable with a box there-in about a horizontal axis through an arc of less than 180° to a position above a horizontal revolvable stacking table having a plurality of stations adapted to successively receive a supply of boxes. Suitable connections are provided between a counting mechanism and the stacking table through 30 which the latter is revolved to bring an empty station beneath the grippers as soon as a predetermined number of boxes has been deposited at the preceding station.

These and many other important features 40 of this invention will appear from the following description read in connection with the accompanying drawings and will be particularly pointed out in the appended claims.

Figure 1 of the drawings shows a side elevation of a preferred form of the invention;

Figures 2, 3, and 4 are detailed views of the grippers and the actuating means there-for; and

Figure 5 is a plan view of the stacking 50 table.

The general features of the type of box forming machine herein shown are described in detail in my prior patent. Only such portions of the mechanism referred to as intimately related to the novel features of the

invention will be described herein, and for further information as to the details of construction of the machine, reference may be made to the said patent.

In its general aspects, the box forming 60 machine includes a fixed male die member 2, about which are formed the blanks from which the trays or boxes are formed. Mounted for cooperating with the die member 2 is the female blank bending and forming mechanism consisting of the presser foot 4 adapted to hold the blank upon the top face of the die, and blank folding members 6 arranged to bend the blank about the die member in the manner clearly set forth in 70 the patent above referred to.

After the formation of a box, the folding mechanism and the pressure plate are elevated above the die, and the box is ready to be removed. To this end, a stripper bar 75 10 is arranged to reciprocate vertically along one side of the die 2, the upper end of the bar moving in a slot 12 provided in one side of the die head. The stripper bar 10 is actuated by a link 14 connected at one end to the lower end of the bar and at its other end to a second link 16 pivoted to the frame of the machine (not shown) at 18. The link 16 is provided at its free end with a roller 20 arranged in the path of a cam 22 upon a main 80 drive shaft 24, a spring 26 serving to maintain the roller 20 in contact with the cam.

From this construction, it will be evident that rotation of the shaft 24 will elevate the bar 10 to lift one side of the formed box from 85 the die 2 at a predetermined time in the cycle of operation of the machine.

The gripping mechanism for receiving and transferring the stripped box from the die will now be described. Mounted in suitable 90 bearings on the side of the die opposite to the stripping member is a shaft 28 having a longitudinal groove 30 therein for the reception of a fixed gripper jaw 32, suitable means being provided for retaining the gripper element within the groove, such as rivets 34.

One side of the gripper jaw 32 is formed with ears 36, in which is fixed a short shaft 38 adapted to pivotally support a movable gripper jaw 40 which cooperates with fixed 100 jaw 32 in a manner hereinafter described.

The movable gripping jaw 40 comprises a flat plate 42 having the central portion cut away as at 44 to form upstanding arms 46 adapted to cooperate with the jaw 32 to form 110

therewith a pair of relatively movable gripper jaws between which the boxes are held in a manner hereinafter described.

The bottom of the gripper element 40 is formed with alined ears 48 adapted to receive the shaft 38 previously described. Surrounding the shaft is a spring 50, the ends of which bear respectively against jaw 32 and against the lower edge of the movable gripper jaw 40 to yieldingly urge the latter toward the fixed jaw 32.

The movable jaw 40 is provided on one side with a downwardly extending tail or arm 52, the lower end of which is arranged 15 in the path of a cam 54 rotatably mounted upon the shaft 28. From this construction, it will be evident that at a predetermined point in the cycle of operation of the machine, the cam 54 will actuate the movable 20 jaw 40 to move away from the fixed jaw 32.

In order to normally retain the jaws 32 and 40 in open relation, a bar 56 is provided, having an angularly bent end 58 adapted to project beyond the front face of the jaw 32 25 to engage an extension 60 projecting from one side of the movable jaw 40, as clearly shown in Figures 2 and 3. When the bar 56 is engaged with the extension 60, the movable jaw will be locked in open position, 30 as illustrated in Figures 1, 2 and 4.

The bar 56 is pivoted intermediate its length to a boss 62 formed upon the rear face of the fixed jaw 32. The bar 56 is provided upon its lower end with a cam surface 35 64 arranged in the path of the cam 54 previously mentioned. The construction is such that engagement between the cam 54 and the bar 56 will cause the latter to move about its pivot to disengage the end 58 of the bar 40 from the extension 60 on the movable jaw, thereby allowing the spring 50 to close the jaw members. A spring 66 secured at one end to the jaw 32 and connected at its other end to the bar 56 tends to yieldingly pull 45 the upper end of the bar toward the jaws so that whenever the jaws are positively opened by the cam 54, the end 58 of the bar 56 will snap into the path of the projection 60 to hold the jaws in opened position until 50 the bar 56 is again moved about its pivot by the cam 54 in the manner previously described.

The cam 54 for opening the gripper jaws is formed integral with a sprocket wheel 68, 55 which is continuously driven from a sprocket wheel 70 upon the drive shaft 24 by means of a drive chain 72.

In the initial or starting position, the gripper jaws are in the position shown in 60 Figure 1, the jaws being open and the fixed jaw 32 being adjacent to and in contact with one face of the die 2. When a box is molded about the die, the jaw 32 will lie between one side of the box and the die in a manner 65 clearly understood. The operation of the

parts is so timed that after the stripper 10 has elevated one side of the box from the die, the movable jaw 40 will be released by the bar 56 to grip the box against the fixed jaw 32.

A further step in the operation of the machine is to move the gripper jaws with a finished box therein bodily about the shaft 28 to transfer the box away from the die. To this end, a crank arm 74 is fixed to one end of the shaft 28. The arm 74 is connected by a link 76 to one end of a bell crank 78 pivoted to a stationary part of the machine at 80. The other end of the bell crank 78 is connected by a link 82 with a second bell crank 84 mounted upon a stationary pivot 86. The free end of the crank 84 is provided with a roller 88 adapted to engage a cam 90 upon the drive shaft. By the rotation of the shaft 24, the shaft 28 will be actuated through the mechanism described to swing the gripper jaws into the position indicated by dotted lines in Figures 1 and 4. As will be seen from Fig. 1, the cams are so related that shaft 28 will have rotated through an appreciable angle before cam 54 has moved tail 56 to permit the jaws to snap together. Further rotation of the drive shaft will cause the jaws to be opened by the cam 54 acting upon the tail 52 of the movable jaw, thereby releasing the box therefrom.

As previously stated, this invention contemplates the provision of a stacking and counting mechanism by means of which the finished boxes are arranged in piles containing a predetermined number, each pile being then automatically conveyed away from the stacking station. The mechanism for performing these operations will now be described.

Conveniently located at one side of the box forming mechanism is a box receiving table or turret indicated generally at 95. The turret 95 is provided with a plurality of radially extending arms 96 on the end of each of which is provided a box receiving and stacking unit 98. The turret is fixed upon a centrally arranged shaft 100 rotatably mounted in vertical bearings 102, one of which is formed in the supporting frame 104, the other being formed in a base member 106. Mounted loosely upon the shaft 100 is a gear 108 formed integral with a friction clutch element 110 adapted to cooperate with the clutch element 112 fixed to the shaft. The gear 108 is driven by a worm 114 upon a horizontal shaft 116 mounted in the frame 104. The shaft 116 is connected to any convenient source of power so as to be continuously driven. The turret 95 will be rotated about the central shaft 100 through the cooperating clutch elements 110 and 112 in a manner clearly understood.

The shaft 100 has fixed thereto a disk member 118 having a plurality of notches 120 in the periphery thereof corresponding in number to the arms 96 of the turret. Pivoted upon the stationary frame as at 122 is a pawl or dog 124 having its inner end slightly bent to adapt it to enter the notches upon the disk 118 to hold the shaft 100 and therefore the turret 95 against rotation. A spring 126 is connected at one end to the dog 124 and at its other end to the frame as at 128 to urge the end of the dog against the periphery of the disk at all times.

The outer end of the dog 124 is provided with a roll 130 which is arranged in the path of a cam 132, the latter being adapted at a predetermined point in the operation of the machine to release the dog from the disk 118 to allow the table to be turned through a quarter of a revolution by the friction clutch elements. The manner in which the cam 132 is actuated will be described in detail hereinafter.

Upon the outer end of each arm of the turret is a horizontal box receiving platform or table 134. The construction and mounting of each of these platforms is identical and a description of one will suffice. Each platform 134 is provided upon its ends with ears 136 having vertical openings therein adapted to receive vertical rods 138 and 140 arising from the upper face of the turret. In the preferred construction, the rod 138 is plane, while the rod 140 is threaded for a purpose hereinafter explained. Pivoted upon the lower face of the platform as at 142 is a thin pawl element 144 adapted to partially surround the threaded rod 140 and enter the grooves therein, a spring 146 serving to yieldingly urge the pawl element against the rod. From this construction, it will be clear that the platform will be connected to the threaded rod so as to be actuated upon any rotative movement of the latter. Adjacent each side of the platform 134 are vertical guide plates 148 adapted to retain the boxes in proper stacked relation upon the platform.

The arrangement of the turret with respect to the forming mechanism is such that when the turret is stationary, one of the platforms 134 will be in position to receive a box from the gripper mechanism after the latter has been swung to its delivery position, as illustrated in Figure 1. Upon the delivery of each box to the platform, the threaded rod 140 is automatically rotated to lower the platform an amount sufficient to keep the top of the pile at substantially the same vertical level. To this end, the lower end of the threaded rod is extended through an opening in the turret, flanges 150 being formed thereon above and below the turret whereby the rod is permitted to rotate while held against axial movement.

Upon the end of the rod 140 is mounted a gear 152 adapted to mesh with a stationary gear 154 beneath the delivery station. The gear 154 is mounted upon a vertical stub shaft 156 suitably supported in the frame of the forming mechanism. The shaft 156 is provided with a spiral gear 158 driven by a worm 160 carried by a horizontal shaft 162. This latter shaft is driven from the main drive shaft 24 by a chain 164 trained about suitable sprockets provided upon the shaft.

As hereinbefore explained, one revolution of the shaft 24 will cause the delivery of a box to the stacking table. Simultaneously, the threaded rod 140 will be rotated through the mechanism just described to cause a lowering of the platform 134 an amount necessary to compensate for the latest addition to the pile of boxes.

As further contributing to improved results, this invention contemplates the provision of means for automatically removing the platform from beneath the grippers after a predetermined number of boxes have been deposited thereon. The means whereby such movement is effected comprises a crank arm 166 secured to one end of the shaft 162, the said arm being connected by a link 168 to a pawl carrier 170 pivoted at 172 to one end of the turret frame. The member 170 carries upon the lower end thereof a pawl 174 adapted to engage the teeth in a ratchet wheel 176 loosely mounted upon the shaft 116. The wheel 176 carries upon its inner face the cam 132 through which the locking dog 124 is disengaged from the disk 118 in a manner previously explained. The wheel 176 is formed with a number of teeth equal to the number of boxes which it is desired to have in each pile. Upon the rotation of the shaft 162 which occurs with the delivery of each box, the wheel 176 is advanced one tooth or notch. After a complete rotation of the wheel 176, the cam 132 will move the dog 124 to release the shaft 100, whereupon the turret 95 will be rotated one-quarter of a turn by the friction clutch elements 110 and 112. During this movement of the turret, the platform containing a pile of boxes will be moved away from the delivery station and the next succeeding empty platform will be moved into box receiving position.

Upon the completion of each pile of boxes, it is evident that the platform 134 on which the pile is supported will have been moved downwardly by the threaded rod 140 to a point adjacent the upper face of the turret. After the finished pile has been removed from the platform, the locking pawl 144 is moved out of engagement with the threads of the rod whereupon the platform can be readily elevated to its initial position.

Since the manner in which the different

parts of the machine operate to perform their functions and the sequence of the operation as a whole have been set forth in connection with the detailed description of the machine, no further description of the operation is necessary for an understanding of the invention.

What I claim and seek to have protected by Letters Patent is:

10. 1. In combination with a box making machine having a fixed male die over which blanks are formed, means for stripping the formed boxes from the die and means for gripping the stripped boxes and transferring them from the die to a stacking table.
15. 2. In combination with a box making machine having a fixed male die over which blanks are formed, means for stripping the formed boxes from the die, a pair of cooperating jaws adapted to receive the boxes as the latter are stripped from the die, and means for moving the jaws to a discharge position.
20. 3. In combination with a box making machine having a fixed male die over which blanks are formed, means for stripping the boxes from the die, a pair of cooperating jaws adapted to receive the boxes as the latter are removed from the die, means for moving the jaws to transfer the boxes away from the die, and means for separating the jaws to release a box carried thereby.
25. 4. In combination with a box making machine having a fixed male die over which blanks are formed, means for stripping the formed boxes from the die, a pair of cooperating jaws arranged adjacent to the die in position to receive the boxes as they are stripped from the die, means for simultaneously rotating the jaws to transfer the boxes away from the vicinity of the die into a delivery position, and means to open the jaws to release a box carried thereby after the jaws have been moved into a delivery position.
30. 5. In combination with a box making machine having a fixed male die over which blanks are formed, a movable member adapted to strip the formed boxes from the die, gripping members adapted to receive the stripped boxes from the die, and means for moving said gripping members to a discharging position.
35. 6. In combination with a box making machine having a fixed male die over which blanks are formed, means for stripping the formed boxes from the die, a pair of pivoted cooperating jaws adapted to receive the boxes adjacent the die, means for holding the jaws open to receive a box therein,

means for releasing the jaws to clamp a box, means for simultaneously moving the jaws to transfer a box away from the vicinity of the die, and means to open the jaws to release a box therein.

7. In combination with a box making machine having a fixed die over which blanks are formed, a jaw member adapted to lie between the blank and the die while the blank is being formed, a movable member adapted to strip the formed boxes from the die, a second jaw member pivoted to said first mentioned jaw member and cooperating therewith to grip the stripped boxes, and means for simultaneously moving said jaws to a discharge position.

8. In combination with a box making machine having a die over which blanks are formed, means for stripping the formed boxes from the die, a rotatable shaft adjacent the die, a fixed gripper jaw mounted upon said shaft and adapted in one position to engage a side of said die, a movable gripper jaw pivoted to said fixed jaw, means for normally urging said jaws together, means for holding the jaws separated to receive a box therein, means for rotating the said shaft to carry the jaws away from the vicinity of the die, means for releasing the jaws when they have moved into delivery position, and means for rotating the shaft in an opposite direction to return the jaws into a box receiving position.

9. In combination with a box making machine having a die over which blanks are formed, means for stripping the formed boxes from the die, a rotatable shaft mounted adjacent said die, a fixed gripper jaw secured to said shaft and adapted to engage one side of said die, a movable gripper jaw pivoted to said fixed jaw, means for normally urging said jaws together, a downwardly extending tail formed on said movable jaw, means adapted to engage said tail and move the movable jaw away from the fixed jaw, a bar pivoted upon the rear face of the fixed jaw having an angular end adapted to project beyond the front face of the fixed jaw in the path of the movable jaw to hold the jaws in spaced relation to receive a box therebetween, means adapted to move the bar about its pivot to disengage the movable jaw and permit the jaws to close, and means for moving the gripper jaws to transfer a box carried thereby away from the vicinity of the die.

In testimony whereof I affix my signature.

CHARLES H. VON GLAHN.
